EXTRUSION MOLD

Alfonz Kunz, Fuzfo, Hungary

Application August 24, 1937, Serial No. 160,646
In Hungary August 28, 1936

8 Claims. (Cl. 18—14)

The present invention relates to a device for the preparation of gunpowder in tube form.

The device according to the invention consists of a group of separate replaceable molds in a common carrier and independent of one another, each of which consists of a die and a needle independent of the die.

One object of the invention is to provide an extrusion mold unit which comprises a die, a needle mandrel for said die, and a bridge piece adapted freely to seat upon said die and slidably to receive said needle mandrel, so that said component parts can be assembled or separated merely by relative movement in a common axial direction.

Another object of the invention is to provide an extrusion apparatus comprising a common carrier plate for a plurality of multi-part extrusion molds of the kind described in the preceding paragraph in which each of said plurality of molds is slidably held so that the component parts of said mold are retained in their relative operative positions against force exerted thereon by the extruded material.

The drawing shows one form of construction of the device according to the invention in which Figure 1 shows the carrier in cross-section without molds. Figure 2 is a plan of the carrier with molds set in. Figure 3 is a longitudinal section of a mold on an enlarged scale and Figure 4 is a plan of the mold according to Figure 3.

In the carriers 11 are borings parallel one to the other, the upper parts 12 of which are larger in diameter than the lower parts 13. The upper part of all the borings 12 opens into an annular recess 14 formed in the upper side of the carrier.

In each boring 12 of greater diameter is inserted a mold according to Fig. 3, which seats itself against the shoulder 15 formed at the junction of the larger bore 12 with the smaller bore 13.

Each die consists of a die part 16 containing the die opening, a bridge 17, a needle 18, and a needle holder 19. In the inner part of the die is a conical annular space 21 which opens out into the mouthpiece 20, in which space opens the cylindrical space 22 of the bridge part 17 resting on the dies. In the middle part 23 of the part 26 of the bridge 17 which contain the needle holder 19 there is also a cylindrical boring. The upper end of the boring 22 open into the boring 24 of the bridge which is conically widened out in an upward direction. The needle holder is also at its lower end 25 conical and has a handle 26.

The needle holder is bored longitudinally; in

this boring passing the whole length of the holder is the needle 18. The needle is held in the needle holder both above and below and the lower end of the needle holder extends so deeply that only the short end of the needle lying in the die is not held. As this part of the needle is very short the needle is very rigid against any bending strain from the side.

The boring 13 of the carrier is appreciably greater in diameter than the opening of the die, so that the tube proceeding out of the die passes on into the boring 13 without touching the walls thereof.

The device above described is suitable for the preparation of a tube-shaped gunpowder of different wall thicknesses or with different inner diameters. With the same outer diameter gunpowder with different thicknesses of walls can be prepared by means of this device simply by changing the needle fixed in the die. Different outer diameters of the gunpowder can also be made by changing the die.

The borings 12 are so adjusted that they can take different dies. If the needle or the die is damaged only the damaged part requires to be replaced. Now in the device as above described very fine dies and very thin needles may be used so that this device is applicable in the preparation of tube-shaped molded gunpowders with exceptionally thin walls. Furthermore the preparation of tube-shaped molded powder with any desired thickness of wall does not present any difficulties in the device above described. The needle is accurately held in the needle holder and the precise positioning of the bridge and needle holder ensure a central position for the needle.

I claim:

1. Extrusion apparatus for operation at high pressures for the preparation of tubular bodies of gunpowder, comprising, in combination, a carrier having a plurality of mold-receiving recesses in its upper surface, each said recess conjoining at its bottom wall with an opening of reduced cross sectional area which opens into the lower surface of said carrier, a plurality of dies slidably positioned in said recesses and resting freely upon the bottom wall thereof without binding engagement between the outer wall of said dies and walls of said recesses, each said die having an opening extending from top to bottom thereof and terminating at its lower extremity in an extrusion opening of reduced diameter, a plurality of tubular bridge pieces slidably positioned in said recess and resting freely upon the tops of said dies without connection between said

bridge pieces and said dies or binding engagement between the outer walls of said bridge pieces and walls of said recesses, said bridge pieces each having a central sleeve supported by 5 radial arms so as to lie co-axial with the extrusion opening of the corresponding die, a plurality of shouldered needle holders slidably positioned in said sleeves, and a plurality of mandrel needles co-axially mounted in said holders and 10 extending into said die extrusion openings co-axially therewith while the shoulder of each needle holder rests freely upon the top of its corresponding sleeve and the lower extremity of each said holder extends downwards to act as a support to stiffen the operative portion of said 15 needle.

2. Extrusion apparatus as claimed in claim 1, wherein each needle holder comprises a handle bored longitudinally thereof to receive a mandrel 20 needle, and having its lower portion shouldered and resting freely upon said sleeve of the corresponding bridge piece without binding engagement between the mutually contacting surfaces of said holder and said bridge piece, and a needle 25 passed through the bore of said handle and projecting from the lower extremity thereof to form the needle mandrel lying co-axially in the extrusion opening of the corresponding die.

3. Extrusion apparatus as claimed in claim 1, 30 wherein each needle holder comprises a handle bored longitudinally thereof to receive a mandrel needle, and having its lower portion reduced in width and slidably positioned in the sleeve of the corresponding bridge piece without binding 35 engagement between the surface of the reduced portion of said handle and inner wall of said sleeve, said handle extending downwards with its lower extremity terminating as near as is practically possible to the upper extremity of the extrusion 40 opening in the corresponding die.

4. Extrusion apparatus as claimed in claim 1, wherein the central sleeve of each bridge piece extends downwards into the die and supports the needle handle against the lateral thrust of the 45 extruded material.

5. Extrusion apparatus as claimed in claim 1, wherein the said carrier comprises a solid plate having a greater depth than that of said mold.

6. Extrusion apparatus as claimed in claim 1, 50 wherein the cross sectional areas of the open-

ings which lead from said mold-receiving recesses to the bottom of said carrier are greater than the cross sectional areas of the corresponding extrusion openings in said dies.

7. Extrusion apparatus for operation at high pressure for the preparation of tubular bodies of gunpowder, comprising, in combination, a carrier plate having a plurality of cylindrical mold-receiving recesses in its upper surface, each said recess terminating intermediate the upper and lower surfaces of said plate and conjoining at its bottom wall with a passage of reduced diameter which opens into said lower plate surface, a plurality of cylindrical dies slidably positioned in said recesses and resting upon the bottom of 15 said recesses, each said die having a frusto-conical opening therein tapering downwards and conjoined at its lower extremity with a cylindrical extrusion passage which opens into the lower surface of said die, a plurality of annular bridge pieces 20 slidably positioned in said mold-receiving recesses and seating upon the tops of said dies, each of said bridge pieces having a central, co-axial sleeve mounted upon radial arms secured to the body 25 of said bridge piece, said sleeve extending downwards and projecting into said frusto-conical opening in said die, a plurality of handled needle holders each bored longitudinally to receive a mandrel needle and having its lower portion reduced to form a shouldered member which is 30 slidably positioned in a corresponding bridge piece sleeve with the shoulder thereof seated upon the top of said sleeve, said reduced portion of said handle extending downwards and projecting into said frusto-conical opening in said die, 35 and a plurality of needles each passing longitudinally through said bores in said handles and projecting from the lower extremities thereof co-axially into the extrusion passages of said dies, said extensions of said sleeves and said handles serving to support said mandrel needles against the lateral thrust of the extruded material.

8. Extrusion apparatus as claimed in claim 7, wherein in each mold the said extensions of said needle holders and said sleeves are bevelled to 45 provide in conjunction with the inner wall of said die a smoothly tapering passage from the upper portion of said die to its extrusion passage.
